UNITED STATES PATENT OFFICE

JOHN GELOSO, OF LAWRENCE, MASSACHUSETTS, ASSIGNOR TO PILOT RADIO & TUBE CORPORATION, OF BROOKLYN, NEW YORK, A CORPORATION OF DELAWARE

DESIGN FOR A CABINET FOR RADIO RECEIVERS

Application filed November 14, 1930. Serial No. 37,653. Term of patent 3½ years.

To all whom it may concern:

Be it known that I, JOHN GELOSO, a citizen of the Kingdom of Italy, residing in the city of Lawrence, in the State of Massachusetts, county of Essex, have invented a new, original, and ornamental Design for a Cabinet for Radio Receivers, of which the following is a specification, reference being had to the accompanying drawing, forming part thereof.

The figure is a front perspective view of a cabinet for radio receivers, showing my new design.

The rear portion of the cabinet not shown in the drawing is open.

I claim:

The ornamental design for a cabinet for radio receivers, as shown and described.

JOHN GELOSO.
